ALLEVIATING CONTRIVANCES FOR SILOS,
DRYING SHAFTS AND THE LIKE

Frans Gustaf Hugo Lamke, Stockholm, Sweden

Application April 1, 1957, Serial No. 650,039

1 Claim. (Cl. 214—17)

The present invention relates to silos, drying shafts and the like, and more particularly to contrivances for taking up the load of granular or powdered materials stored or otherwise contained in such shafts.

The main object of the invention is to provide an alleviating contrivance for shafts of the type referred to, which ascertains uniform sinking of the materials through the shaft when the material is discharged therefrom. Thus, the invention has for its object to remove the drawbacks which are connected with the known ridge-like beams which have been used in silos and drying shafts for taking up the load of the material stored in the silo or shaft, for example to relieve the discharging means located at the bottom of the silo or shaft. The upper side of a beam of the known kind has the form of two planes disposed at right angles to one another, and the space between two adjacent beams will thus vary in a manner such that the free cross section of the shaft is reduced. Thus, the material passing between the beams from the plane through the top to the lower edge of the beams will have to move in continuously decreasing spaces, and this restriction of the free cross section causes an even sinking of the material passing down the shaft and may cause the formation of bridges and other disadvantages. It is such disadvantage, in the first place, that should be removed by the present invention.

A further object of the invention is to provide a combination of gratings capable of surely taking up the load of the contents of relatively high silos, shafts and the like.

A still further object of the invention is to provide a contrivance for taking up the load substantially in the lower portion of a shaft to relieve underlying means such as discharging means from the load of materials of any kind consisting of grains or particles of a most varying size, and particularly material in ground condition.

A further object of the invention is to provide gratings for shafts which immaterially restrict the free cross section of the shaft.

According to the invention the contrivance comprises a grating of inclined plates or the like extending transversely through the shaft, said plates being so arranged that the space between an arbitrary pair of adjacent plates has a constant or nearly constant cross section, or a cross section possibly flaring in the direction of movement of the material passing between said plates. Material passing from the upper edge of such a row to the lower edge thereof consequently moves at a uniform velocity in the various spaces between the plates, inasmuch as the free cross section is constant, and the invention therefore involves the solution of the problem of attaining an even and uniform sinking of the material in the shaft. If the shaft is provided with such inclined plates evenly distributed along the whole of its cross section, a uniform discharge of the material in the lower opening of the shaft will result in that the material passes through the arrangement of plates at the same velocity in various parts

2

of one and the same horizontal section through the shaft.

If all plates in the horizontal portion of the shaft, wherein the grating is located, are straight and extend in parallel to each other, the load of the superimposed material will give birth to forces on the plates that have horizontal components directed in the same direction.

These forces consequently tend to displace the plates horizontally toward one side of the shaft. To prevent this, the plates located on one side of a middle plane may 10 slope in the one direction to the horizontal plane, while the plates located on the other side slope in the opposite direction, the angles of inclination being then in both cases preferably equal numerically, so that the horizontal component of the forces acting on one side of said middle 15 plane by reason of the load of the contents of the shaft on the contrivance will be balanced by the horizontal component of the forces acting on the other side.

Further features of the invention will appear from the following description of a few forms of embodiment

20 illustrated in the accompanying drawings. Fig. 1 shows a vertical central section through a portion of a shaft provided with an alleviating contrivance according to the invention, and Fig. 2 shows on a larger scale and in vertical projection a few plates comprised in said contrivance. 25 Fig. 3 shows, in the same manner as Fig. 1, a second embodiment of the invention, and Fig. 4 shows a corresponding horizontal projection with the upper grating partly removed. Figs. 5 and 6 show a third embodiment in vertical section and in a corresponding horizontal 30 projection, respectively.

In the drawing, 1 designates the wall of a silo shaft having the alleviating contrivance arranged therein. In the embodiment according to Figs. 1 and 2, said contrivance consists of two rows of plates located above one 35 another, each of said rows forming a grating. Two arbitrary adjacent plates 2, 3 in the upper grating extend in parallel to each other, so that a passage 4 is formed between them, said passage broadly taking the form of a parallelogram in the transverse vertical section 40 shown. The free passage section within each row of such parallel plates is consequently constant from the upper edge 5 of the plates counted to the lower edge 6. The plates extend in each horizontal grating in parallel to one another and bridge the whole cross section of 45 the shaft.

It is of importance that the upper edge of one plate of a pair of arbitrary adjacent plates projects past the lower edge of the other plate in the pair, that is to say, in a manner such that the projections of the plates 50 on a horizontal plane overlap. Otherwise, the material in the shaft could pass between the plates without being guided by the latter, whereby the sinking of the material in the shaft could become irregular.

The plates take up the load from the superimposed 55 material in the shaft, which at every individual plate may be represented by a force k acting on the upper side of the plate and directed at right angles thereto. By reason of the inclination of the plate, said force tends to displace the plate not only downwardly but sideways as well. As shown in Fig. 1, the plates, such as the plates 2, 3, located in the upper row on one side of a middle plane of the shaft are inclined in one direction to the horizontal plane, while the plates 7, 8 located on the other side of said diagonal plane slope in the opposite 60 direction. In both cases, the angle of inclination v is numerically the same, for which reason the horizontal component h of the forces k , which on account of the load of the contents of the shaft on the plates act on one side of the diagonal plane, is balanced by the horizontal component h_1 of the forces k_1 acting on the other side. The sloping plates are kept together by vertical 65 70 75 80 85 90 95

plates 9 extending at right angles to them, and these latter plates may be anchored with their ends in opposite walls of the shaft. The ends of the plates may also be anchored in the shaft wall or in a frame 9¹ extending all around. The frame forms together with the sloping and vertical plates a grating which covers the cross section of the shaft.

In the construction according to Fig. 1, the plates 10, 11 of the lower grating slope in a direction opposed to that of the plates in the upper grating, but the longitudinal directions of the plates of the two gratings parallel each other. In this construction the lower plate edges of the upper grating may be located right above the upper edges of the lower grating, but the downflow of the material between the plates is facilitated, if there is a small displacement. The plates are arranged with approximately the same pitch in the grating located above one another, but the plates of the one grating are displaced by a fraction of the pitch of the plates in the other grating. This is elucidated in Fig. 2, where the pitch of the plates is denoted by α and the plates 10, 11 of the lower row are displaced by $\frac{1}{3}\alpha$ relatively to the plates 2, 3 of the upper row.

Figs. 3-4 show an embodiment, wherein two horizontal gratings 12, 14 above one another the plates of the upper grating 12 extend with their longitudinal direction at right angles to the plates of the lower grating 14. Hereby a further distribution of the load is obtained. Both in the upper and in the lower grating the plates are inclined on one side of the middle plane in a direction opposed to that of the plates on the other side, whereby the resultant of the horizontal components of the load on the various plates becomes equal to zero.

It should be noted that the shaft wall projects forwardly over the gratings at the ends of the plates so as to cover here to a requisite extent those downwardly converging spaces 15 which are formed between the outermost sloping plates and the shaft wall.

The invention is not limited to the embodiments shown and described, which only represent elucidating examples. The angle of inclination v may vary according to the nature and particularly the angle of repose of the ma-

5 terial in the shaft, so that for a material such as rape-seed, which has rather a small angle of repose, plates are arranged at a lesser inclination (smaller angle v) than for a material such as flour, which has a greater angle of repose.

In the embodiment shown in Fig. 5, the plates 16 run on concentric circles so as to extend along conical surfaces. They are kept together by radial bracing plates 17, at least some of which extend into a central conical member 18. This member may be connected to a supporting spider 19 through a central rod 20. The spider is located at a distance above the grating.

What I claim is:

A granular material load supporting apparatus comprising a cylindrical shaft having vertical walls, a horizontal grating traversing said shaft intermediate the upper and lower ends thereof, said grating consisting of a central conical member, a plurality of radially-spaced circular plates concentrically mounted about said central conical member and sloping radially-outwardly from their top edges to their bottom edges, one of two adjacent plates having its top edge extending horizontally past the lower edge of the other plate so that the projections of the plates on a horizontal plane will overlap, any two plates forming therebetween a space having a constant cross-section, and radially-arranged bracing plates connecting said circular plates to said central conical member; spider means in said shaft above said grating; and means connecting the central conical portion of said grating to said spider means, said shaft having a horizontal cross-sectional area below said grating which is at least as great as the horizontal cross-sectional area above the grating.
